(57) **CLAIM**

An ornamental design for a trailer hitch cargo carrier, as shown and described.

DESCRIPTION

FIG. 1 is a rear view of my trailer hitch cargo carrier.
FIG. 2 is a front view of my trailer hitch cargo carrier.
FIG. 3 is a side view of my trailer hitch cargo carrier.
FIG. 4 is a top view of my trailer hitch cargo carrier.
FIG. 5 is a bottom view of my trailer hitch cargo carrier; and, FIG. 6 is a perspective view of my trailer hitch cargo carrier. The broken lines represent unclaimed subject matter and form no part of the claimed design.
